The ornamental design for a storage cabinet, as shown and described.

DESCRIPTION

FIG. 1 is a left side elevational view of a storage cabinet showing my new design; the undisclosed right side elevational view thereof being a mirror image of the disclosed left side;

FIG. 2 is a front elevational view thereof;

FIG. 3 is a top plan view thereof;

FIG. 4 is a bottom view thereof; and

FIG. 5 is a cross-sectional view taken along line 5—5 of FIG. 2.
